CONTAINER AND DISPENSER

Henry Kermian, San Bernardino, Calif.

Application June 3, 1935, Serial No. 24,604

8 Claims. (Cl. 221—67)

This invention relates to a novel form of container capable of being destroyed after use, and to a dispensing means whereby the content of the container may be discharged in increments 5 without subjecting the contents to the action of air or contamination from other sources. The invention is particularly directed toward a container and dispensing means whereby a relatively viscous fluid or emulsion such as mayonnaise, may be dispensed in a sanitary manner and all of the contents of the container removed therefrom without exposing such contents to contaminating influences.

Heretofore, bulk materials such as mayonnaise, 15 have been dispensed from crocks or jars into which a utensil such as a spoon, was dipped in order to withdraw the desired quantity. During such withdrawal, the contents of the container were exposed to the atmosphere, permitting various forms of impurities, dust, etc., to be deposited therein. Furthermore, it was extremely difficult, if not impossible, to remove all of the contents of such containers.

The present invention, however, relates to a 25 form of container which is destructible, thereby preventing its repeated use. Furthermore, during the dispensing operation, the mayonnaise is discharged from the container into the smaller package delivered to the ultimate consumer but 30 at no time is the bulk of the mayonnaise exposed to contaminating influences. Moreover, the dispensing unit is readily removable from the container for sterilizing purposes.

These and other advantages will become apparent from the detailed description of a preferred form of container and dispensing apparatus described hereinafter. In such description, reference will be had to the appended drawings, in which:

40 Fig. 1 is a front elevation of the entire dispensing device, including the container, stand, etc.

Fig. 2 is a side elevation, partly in vertical section.

45 Fig. 3 is an enlarged vertical section taken along the plane III—III of Fig. 1.

Fig. 4 is an enlarged transverse section taken along the plane IV—IV of Fig. 3.

Fig. 5 is a transverse section through the 50 front of the dispensing device, the plane being taken along the plane V—V of Fig. 3.

Fig. 6 is a bottom view of the dispensing device shown in Fig. 3.

55 Fig. 7 is a side elevation of the closure member used on the feeding device.

Fig. 8 is a representation of the gasketing strip used in the apex end of the container.

It is to be remembered that in the transportation and handling of a product such as mayonnaise, the product needs be handled with care as it is possible to cause separation of the ingredients constituting the product by undue agitation or the like. For this reason, the dispensing apparatus has been particularly designed to permit the discharge of quantities of mayonnaise 10 from a container without subjecting it to undue agitation or changes in pressure.

As shown most particularly in Figs. 1 to 3 inclusively, the entire apparatus comprises a conical stand 1 provided with a vertically extending 15 opening 2 and a horizontal rest spaced from the bottom of the stand 1. The rest may include a trough-like member 3 supported by means of horizontal braces 4 and 5 attached to the inner walls of the stand 1. Preferably, the braces 4 20 and 5 are also attached to reinforcing legs 6 and 7 which may terminate at the bottom in vacuum grip or other antiskid supporting members 8. The legs 6 and 7 and the rest 3 are proportioned so as to place the feeder, generally indicated at 10, 25 a sufficient height above the bottom of the support 1 to permit the introduction of small containers into which the mayonnaise is to be discharged.

The feeder 10 comprises a cylindrical body 30 portion provided with a bore 11. The lower wall of the body portion may be hexagonal in cross section so as to permit its reception and retention in a similarly shaped rest 3. Furthermore, the lower wall of the body may be provided with 35 a protuberance 12 adapted to extend through a port 13 formed in the rest 3 and be held in such rest by means of a sliding lock 14 provided with bifurcated ends and a finger grip 15, as more clearly shown in Fig. 6. The rear 40 wall 16 is preferably inclined to the vertical, as shown in Fig. 3, whereas the front member is provided with an outlet 17. The front member indicated at 18 may be removably attached to the body of the device as by means of the screws 45 19, a suitable gasket 20 being inserted between the front portion 18 and the end of the body portion 10. The side walls of the body portion 10 may be provided with inwardly extending keys 21 and 22 adapted to slidably engage with notches 50 cut in a piston 23 slidably positioned within the bore 11. The piston 23 preferably lies in a plane parallel to the rear wall 16 and is therefore inclined to the vertical. The piston 23 is attached to a rod 24 extending through the front member 55

18 and terminating in a knob or handle 25. The piston rod 24 may also pass through a suitable packing gland, indicated at 26.

The front member 18 is provided with a downwardly curved discharge port 17. At either side of said port vertical bores are provided adapted to receive pins, such as the pin 27 upon which a closure member 28 is pivoted, the closure member being adapted to close the port 17. The pivot pin 27 is pressed upwardly in a yielding manner by reason of a spring 29. The pin 30, provided with a knob 31 at its lower end, is also pressed upwardly in a yielding manner by a similar spring 32. The closure member 28 (shown in detail in Figs. 6 and 7) is provided with a handle 33 and a tapering finger 34 forming a recess or bay 35 adapted to receive the pin 34. The tapered structure of the finger 34 insures positive closure of the member 17 by the member 28 when said member 28 is pivoted upon the pin 27 by the operator.

The feeding device is also provided with an inlet port indicated at 36 which preferably is positioned at a point adjacent the rear wall 16. The diameter of the port 36 should be insufficient to extend over the entire length of the bore 11 and preferably the port 36 does not extend beyond the mid length of the bore 11. The inlet port 36 may be provided with internal screw threads as indicated at 40, adapted to threadedly engage with the metallic threaded member 41 carried upon the apex portion of the container 42.

The container 42 is preferably of parchmentized paper or waterproofed board and is conical in form. The base of the container may be formed of a fiberboard disc 43 provided with a beveled edge, said disc being inserted into the base of the cone and stapled thereto as indicated at 44. If desired, an insoluble adhesive may also be used. Great difficulty has been experienced in placing a cap upon the apex of the cone. It has been found, however, that a molded thin metal threaded cap, such as the cap 41, may be firmly attached to the apex of the container 42 by first cementing a strip or strips around the apex end of the cone, as indicated at 45. These strips 45 are cut along a curve somewhat as indicated in Fig. 8. After being cemented upon the cone 42, the metal cap member 41 is slipped thereover and crimped at 46 and 47. This construction retains the threaded metallic end member 41 firmly upon the cone.

In use the container 42 is filled with mayonnaise or similar substance and the metallic cap 55 is screwed upon the apex end in contact with the threaded member 41. These containers rest on the broad base 43 and are relatively stable. Five gallon containers of this shape are readily handled. When it is desired to install the completed device in a store, the feeding device 10 is threadedly connected to the apex of the container 42 and the entire assembly then positioned within the stand 1. The rest 3 supports and locks the feeder 10 in position. A part of the weight 60 of the container is supported by the upper end of the stand 1. By opening the closure member 28 and manipulating the plunger 25, mayonnaise is withdrawn from the container and discharged through the spout 17. As the inlet 36 65 is positioned in the rear half of the feeder 10, any pendent mayonnaise is drawn back into the feeder 10 upon rearward motion of the plunger 25. Mayonnaise that may have slipped between 70 the rear wall 16 and the face of the piston 23

(while the piston was in its forward position) moves upwardly and over the upper edge of the piston 23 when such piston is moved rearwardly. By reason of the forwardly inclined rear wall and piston, the mayonnaise performs this movement 5 smoothly and without undue agitation so that no separation or breaking of the mayonnaise emulsion results. Sufficient air appears to be admitted through the container to permit uninterrupted gravity flow into the feeder. If desired, however, a few pin holes may be made adjacent the top 43 after the container 42 and the feeder 10 are in position.

Although a specific form of feeding device has been described, it will be obvious to those skilled in the art that numerous changes may be made in its construction. The essential elements of my combination are a stand adapted to receive and hold a dispenser, together with a container which is also supported by said stand.

All changes and modifications coming within the scope of the appended claims are embraced thereby.

I claim:

1. An apparatus for containing and discharging mayonnaise and the like, comprising: a stand having an enlarged bottom and a restricted top and provided with a substantially vertical opening in the wall thereof, and a horizontal rest spaced from the bottom of the stand; a container provided with an enlarged base and a restricted top portion having an opening therein, and a feeding device attached to the top portion of said container, said container and feeding device being adapted to be removably introduced 35 while in inverted position into the stand through said vertical wall opening, said feeding device being removably attached to said rest, said conical container being supported and stabilized by the top of said stand at a point between the top and 40 base of said container.

2. An apparatus for storing and discharging mayonnaise and the like, comprising: a stand having an enlarged bottom and a restricted top, a substantially vertical opening in the wall of 45 said stand, a container provided with an enlarged base and a restricted top portion having an opening therein, a feeding device removably attached to the top of said container, and a restraining means within said stand adapted to engage with 50 said feeding device when said container and feeding device attached thereto is introduced in inverted position into the stand through said restricted top and vertical wall opening, said container being stabilized by the top of said stand at 55 a point between the top and base of said container.

3. An apparatus for storing and discharging mayonnaise and the like, comprising: a stand having an enlarged bottom and a restricted top 60 provided with an upwardly and outwardly flaring lip, a substantially vertical opening in the wall of said stand, a container provided with an enlarged base and a restricted top portion having an opening therein, a feeding device removably attached to the top of said container, and a restraining means within said stand adapted to engage with 65 said feeding device when said container and feeding device attached thereto is introduced in inverted position into the stand through said restricted top and vertical wall opening, said container being supported and stabilized by the outwardly flaring lip of said stand.

4. In a device of the character described, the combination of a stand provided with a vertically 70

extending opening and a rest positioned therein in spaced relation to the bottom of the stand, a destructible container provided with a base, sides tapering to an opening and an externally threaded 5 lip around said opening, a feeding device threadedly connected to said container lip, said feeding device being removably insertable into said stand and onto said rest while attached to said container, by way of said vertically extending opening, and means for locking said feeding device upon said rest while said container is supportingly retained by the top of said stand.

10 5. In a device of the character described, the combination of a stand provided with a vertically extending opening and a rest positioned therein in spaced relation to the bottom of the stand, a conical destructible container provided with an externally threaded lip, a feeding device threadedly connected to said container lip, said feeding 15 device being provided with a horizontal bore, an inlet port communicating with said container in the rear half of said bore, a forwardly inclined rear wall, a forwardly inclined reciprocably mounted piston within said bore, and a valved 20 outlet in the front wall of said bore, and means for locking said feeding device upon said rest while said container is supportingly retained by the top of said stand.

25 6. In a device of the character described, the combination of a conical stand provided with an enlarged base and a constricted top, a vertically extending opening in the wall of said stand, and a rest positioned therein spaced from the bottom of the stand; a conical fibrous 30 and destructible container comprising a conical body portion, a flat base, a plurality of added thicknesses of fibrous material cemented to the exterior of the body portion at the apex, and a substantially cylindrical lip member crimped over the said added thicknesses and to the body portion adjacent said apex; a feeding device provided with a horizontal bore and an inlet port in the rear half 35 thereof, means for connecting said feeding device at said port with said lip member of said container, said feeding device including a forwardly inclined rear wall, a valved front wall, and a forwardly inclined reciprocably mounted piston within said horizontal bore, and means for locking said feeding device upon said rest while said container is supportingly retained by the top of said stand.

40 7. In a device of the character described, the combination of a conical stand provided with an enlarged base and a constricted top, a vertically extending opening in the wall of said stand, and a rest positioned therein spaced from the bottom of the stand; a conical fibrous and destructible container comprising a conical body portion, a flat base, a plurality of added thicknesses of fibrous material cemented to the exterior of the body portion at the apex, and a substantially cylindrical lip member crimped over the said added thicknesses and to the body portion adjacent said apex; a feeding device provided with a horizontal bore and an inlet port in the rear half 45 thereof, means for connecting said feeding device at said port with said lip member of said container, and means for locking said feeding device upon said rest while said container is supportingly retained by the top of said stand.

50 8. In a device of the character described, the combination of a conical stand provided with an enlarged base and a constricted top, a vertically extending opening in the wall of said stand, and a rest positioned therein spaced from the bottom of the stand; a conical fibrous and destructible container comprising a conical body portion, a flat base, a plurality of added thicknesses of fibrous material cemented to the exterior of the body portion at the apex, and a substantially cylindrical lip member crimped over the said added thicknesses and to the body portion adjacent said apex; a feeding device provided with a horizontal bore and an inlet port in the rear half 55 thereof, means for connecting said feeding device at said port with said lip member of said container, said feeding device including a forwardly inclined rear wall, a valved front wall, and a forwardly inclined reciprocably mounted piston within said horizontal bore, and means for locking said feeding device upon said rest while said container is supportingly retained by the top of said stand.

60 9. A dispensing container for mayonnaise and the like, comprising a conical body portion of fibrous material, a flat base member provided with a conically beveled edge inserted into the base of said cone and stapled thereto, a plurality of added thicknesses of fibrous material cemented to the exterior of the body portion at the apex thereof, and a substantially cylindrical threaded metallic member crimped over said added thicknesses and to the body portion at said apex.

HENRY KERMIN.
